UNITED STATES PATENT OFFICE.

ANDREAS R. BLUM, OF NEWARK, NEW JERSEY.

LIGHTER.

1,108,684.

Specification of Letters Patent. Patented Aug. 25, 1914.

Application filed November 26, 1913. Serial No. 803,091.

To all whom it may concern:

Be it known that I, ANDREAS R. BLUM, a citizen of the United States, and a resident of Newark, county of Essex, and State of New Jersey, have invented certain new and useful Improvements in Lighters, of which the following is a specification.

This invention relates to a lighter, and while it can be of any size, it is particularly adapted for a pocket lighter, that is, the type of lighter that can be utilized for the lighting of cigars and the like, or for any purpose, and can be conveniently folded up and carried in the pocket when not in use.

The particular object of the invention is to provide a compact and safe lighter, the preferred form being made in the shape of a watch, the handle of the lighter projecting as does the stem of a watch, this handle being utilized both for permitting the lid to open and for actuating the lighting device.

The lighter is so constructed that the lid, which springs open when released, is free from its latch at a comparatively slight movement of the handle or stem, and a further considerable movement of the handle actuates the lighting device. This necessitates but one motion of the handle to open the lid and to operate the lighting device, but successive movements can be given to the lighting device, in case the first trial does not cause enough spark, without again closing the lid. Another advantage of this construction is that if the handle is suddenly pushed while the device is in the pocket, it probably might move enough to open the lid, but there would not be an appreciable operation of the lighting or sparking device, which is an advantage over the form of lighter in which the release of the lid completes the lighting operation by reason of the lid flying open. This old type of lighter necessitates a closing of the lid on each trial of ignition and similarly, each release of the lid causes a completion of the operation of the lighting device.

The invention is designed to provide a lighter of substantially flat form, being preferably shaped to resemble a watch, and has a partition to divide it into flat compartments, one of which is adapted to hold the fuel, and the other, which is closed by the main lid, is constructed to hold the lighting device, which device is illustrated in this case as one of the type embodying a sparking wheel which bears on a strip of hard

material whereby their friction causes sparks to fly from their juncture in the direction of the wick.

The invention is illustrated in the accompanying drawing, in which—

Figure 1 is a top view of the lighter with the lid open. Fig. 2 is a section, looking upward, taken on line 2, 2, in Fig. 3. Fig. 3 is a section on line 3, 3, in Fig. 1, with the lighting device shown in elevation.

The invention comprises a casing with the side 10 which is annular, although it is not confined to any particular shape, and hinged at 11, on the top thereof, is the lid 12. The back 13 is removable and is held in place in any usual way, the illustration showing the snap edge 14 which permits the snapping of the back into place, as is the case in watches, whereby the back can be removed to permit access to the chamber 15, this chamber 15 being a fuel chamber formed by the partition 16 which is a plate extending across the casing and providing means for preventing the leaking of fuel from the chamber 15. The fuel chamber is preferably filled, as is usual in this type of lighter, with an absorbent, such as cotton, and has a wick 17 which extends up through a tube 18 and has its end 19 emerging from the top of the tube to provide for its ignition. Forming a proper support for the sparking wheel 20 is an upper plate 21.

The sparking wheel 20 can be of any usual type, being made of steel or other material, and is rotatable, having, adjacent to its edge, a holder 22 for a block 23, this block being of the kind usually employed in this type of device and consisting of any of the alloys or materials used for this purpose, being normally held against the wheel by a spring 24. Rotatable with the sparking wheel 20 is a ratchet-wheel 25 which is engaged by a toothed rack 26 pivoted at one end, as at 27, to one arm 28 of a bell-crank 29, the bell-crank being pivoted at 30 so that it swings on one corner, being held in its normal position by a spring 31 which can be suitably disposed so as to move the bell-crank to its normal position when it is released. The arm 32 of the bell-crank is arranged in line with the end of the stem which projects from the casing. The end of the stem may be of any usual construction to engage the face 33 of the arm 32, but I prefer to equip the end of the stem with a roller 34 mounted in the end of the stem 35,

the stem thus forming a handle which emerges from the side of the casing through the crown 36 and thus resembles the crown of a watch. A ring 37 can be placed in the 5 crown to provide for the holding and suspension of the lighter.

On the inner end of the stem or handle 35 is a latch 38 which engages the lid 12, preferably by means of a recess 39, although any 10 other way of attaching the latch and the lid can be used. The latch is so disposed that when the handle is pressed in a slight distance the latch 38 releases the lid which is swung open by a suitable spring 40. As 15 the handle is pushed in still farther, the roller 34, bearing against the face 33 of the bell-crank, swings the bell-crank and pulls the rack 26 so that the ratchet 25 and the sparking wheel 21 are rotated so that sparks 20 are directed from the contact of the block 23 and the wheel 21 onto the end 19 of the wick. The bent up portion 41 of the top plate forms a housing for covering the inward travel of the latch and also makes a 25 better finish by concealing the end of the bell-crank from observation from the top.

If a lighter of this type is accidentally opened by pressure on the handle while it is in the pocket, the lid might be opened, 30 but nothing further would result, as there would be no danger of the opening of the lid causing the operation of the lighting device, since they are separate. This makes a more desirable lighter than the old type 35 in which, when the lid is released, the lid, by completing its opening, causes the ignition of the wick. It will also be noted that when this lighter is operated and fails to light on the first trial, the handle can be repeatedly pushed in without closing the lid 40 each time.

The device can be cheaply made and its operation is assured on account of its simplicity.

I do not wish to be understood as limiting myself to the particular lighting device shown in the drawing, nor to the particular form of latch illustrated, since minor changes can be made in the details 50 and in the arrangement of the parts without departing from the scope of the invention.

Having thus described my invention, what I claim is:—

65 1. A lighting device comprising a casing, a lid for the casing, a lighting device in the casing, a latch for holding the lid shut, an operating mechanism for the lighting device, and a handle operatively connected to the latch and to the operating mechanism in such a manner that a slight movement of the handle releases the latch and a further movement of the handle actuates the operating mechanism.

65 2. A lighter comprising a casing of sub-

stantially flat form, a plate mounted in the casing and having a passage therethrough for a wick, a lighting device mounted above the plate, an operating mechanism for the lighting device, a handle adapted to actuate the operating mechanism and projecting from the side of the casing, a spring for normally holding the handle and the operating mechanism in inoperative position, a spring for normally forcing the lid open, 70 and a latch mounted on the handle and adapted to hold the lid shut, the latch being so disposed that it releases the lid when the handle is operated but before the handle has traveled a distance sufficient to cause an appreciable movement of the operating mechanism.

3. A lighter comprising a casing of substantially flat form, a lid on the top of the casing and having means for normally swinging it open, a plate arranged horizontally in the casing forming, with the casing, a reservoir for fuel, an ignition point above the plate and connected with the reservoir, a sparking device on the plate adjacent to the ignition point, an operating means above the plate and adapted to actuate the sparking device, a handle sliding in the side of the casing, a latch on the handle and engaging the lid to release the lid on a slight movement of the handle, and an anti-friction connection between the handle and the operating mechanism for actuating said mechanism when the handle is moved beyond the releasing point of the latch. 100

4. A lighter comprising a casing, a rotatable sparking wheel in the casing, a bell-crank arranged to swing in the casing, an operative connection between one end of the bell-crank and the sparking wheel to cause the rotation of the sparking wheel when the bell-crank is swung, spring means for forcing the bell-crank to its normal position, and a handle connected to the bell-crank and projecting from the side of the casing and 105 in sliding relation thereto.

5. A lighter comprising a casing, a rotatable sparking wheel in the casing, a bell-crank arranged to swing in the casing, an operative connection between one end of the bell-crank and the sparking wheel to cause the rotation of the sparking wheel when the bell-crank is swung, spring means for forcing the bell-crank to its normal position, a handle connected to the bell-crank and projecting from the side of the casing and in sliding relation thereto, a lid on the casing, and a latch secured to the handle, said latch being adapted to normally hold the lid shut. 115

6. A lighter comprising a casing, a sparking wheel rotatably mounted inside the casing, a ratchet connected to the sparking wheel, a bell-crank swinging in the casing, a toothed rack pivotally secured at one end to one arm of the bell-crank, said rack en- 125

130

gaging with the ratchet, a spring for forcing the bell-crank to its normal position, and a handle sliding in the side of the casing and having its inner end engaging one face of the bell-crank whereby when the handle is pushed the bell-crank is swung.

7. A lighter comprising a casing, a sparking wheel rotatably mounted inside the casing, a ratchet connected to the sparking wheel, a bell-crank swinging in the casing, a toothed rack pivotally secured at one end to one arm of the bell-crank, said rack engaging with the ratchet, a spring for forcing the bell-crank to its normal position, a

handle sliding in the side of the casing and having its inner end engaging one face of the bell-crank whereby when the handle is pushed the bell-crank is swung, a lid on the casing, and a latch for the lid operated from the handle.

In testimony that I claim the foregoing, I have hereto set my hand, this 15th day of November, 1913.

ANDREAS R. BLUM.
